W. E. KELLY

REAMER

Filed Nov. 22, 1920

FIG. 1

FIG. 2

FIG. 3

FIG. 4

Inventor

William E. Kelly

By J. S. Henkel

Attorney

Patented Mar. 13, 1923.

UNITED STATES PATENT OFFICE.

WILLIAM E. KELLY, OF CLEVELAND, OHIO.

REAMER.

Application filed November 22, 1920. Serial No. 425,811.

To all whom it may concern:

Be it known that I, WILLIAM E. KELLY, a citizen of the United States, and resident of Cleveland, county of Cuyahoga, and State of Ohio, have invented a new and useful Reamer, of which the following is a specification.

My invention relates to reamers which have adjustably inserted cutting blades.

10 Reamers with inserted blades have been made but the constructions heretofore devised have many disadvantages; for instance the blades loosen while in operation, cumbersome or inefficient adjusting mechanism, 15 expensive construction, etc.

The object of my invention is to overcome the disadvantages now found in similar tools and provide a reamer of simple construction, readily adjustable, positive in maintaining its adjustment, and economic of manufacture and of operation.

20 My invention is clearly illustrated in the accompanying drawing wherein Fig. 1 is a side view of a reamer partly broken away to line 1—1 of Fig. 2 to show the construction clearly; Fig. 2 is a section on line 2—2 of Fig. 1; Fig. 3 is a section on line 3—3 of Fig. 1; and Fig. 4 is a side view of a modification partly broken away to a 30 line substantially corresponding to line 4—4 of Fig. 2.

Similar reference characters refer to similar parts throughout the views.

Referring particularly to Figs. 1, 2, and 35 3 which show an adjustable reamer composed of a body 5 having the shank 6, cutters 7, ring 8, washer 9, lock nut 10, and clamp screws 11.

The body 5, made of suitable material and 40 contour, has the slots 12 which have radially parallel walls and an inclined bottom, the threaded portion 13, and the keyway 14. The shank 6 may be formed to any desired contour and length. The body 5 also has 45 slits and is divided at the front end; further description and the purpose thereof will appear presently.

Each cutter 7, made of suitable material, fits snugly into one of the slots 12, has an 50 inclined bottom corresponding to the inclination of the bottom of the slots 12, an inclined face 15 at the rear end, a cutting face 16, and is suitably hardened.

The ring 8, made of suitable material, has 55 a threaded opening fitting to the threaded portion 13 on the body 5, the inclined face

17 the inclination of which corresponds to the inclination of the faces 15 on the rear ends of the cutters 7, and is knurled and has the spanner holes 18 to facilitate its manipulation. The part 8 is named "ring" 60 since it performs the functions of adjusting the cutters longitudinally, of forming an abutment for the rear end of the cutters, and of holding the rear end of the cutters down 65 upon the bottom of the slots, and a name appropriate to all of these functions is not available. It will be seen that the face 17 on the ring 8 as well as the faces 15 on the cutters 7 are inclined more to the radial than 70 to the horizontal axis of the reamer, the purpose thereof being to provide an as nearly as possible square abutment between the cutters 7 and the ring 8 but have sufficient inclination there to hold the rear end of the 75 cutters 7 down upon the bottoms of the slots 12.

The washer 9, made of suitable material and thickness, has a central opening which fits over the top of the threads of the threaded portion 13, and also has the ear 19 projecting into this opening and fitting into the keyway 14.

The lock nut 10, made of suitable material, has a threaded opening fitting to the threaded portion 13 on the body 5.

The clamp screws 11, made of suitable material, are threaded into the body 5 and have the tapered head 20. It will be seen that the taper on the head 20 is comparatively slight; the object thereof being to exert a high pressure sidewise against the divided body portions with a comparatively low turning moment of the screws 11, and to prevent the screws 11 from working loose 95 while the reamer is in operation. These screws 11 are disposed near the front end of the body 5 and between alternate pairs of cutters as clearly seen in Fig. 2.

In line with the screws 11, the body 5 100 has the division slits 21 cut some distance into its front end. To provide more flexibility to the front end of the body 5, the relief slits 25 may also be provided.

The modification shown in Fig. 4 is similar to Fig. 1 except that the shank 6 is omitted and the opening 22 is provided to receive a shank to the end that this reamer may be used in a variety of machines by merely changing the comparatively inexpensive shank. Since all other parts are duplicates of the parts previously described, no 110

detailed mention of these parts is thought necessary and the numerals employed to designate the parts of the previously described reamer have been used to designate corresponding parts in the modification.

The operation of this reamer is as follows: After the parts are made up and assembled as shown, which is the smallest size the reamer will ream since the faces 23, on the cutters and on the ring, are touching, and it is desired to adjust the reamer to a larger size, it is only necessary to release the screws 11, then rotate the ring 8 to slide the cutters forward and consequently outward due to the inclination of the bottoms of the cutters and the slots. When a point is reached where the outside diameter over the cutters corresponds to the size of the reamer required, tighten the clamp screws 11, and then tighten the lock nut 10. This tightening of the lock nut 10 in no manner effects the ring 8 rotatably since the washer 9, which is prevented from rotation by the ear 19 projecting into the keyway 14, is interposed between the lock nut and the ring and prevents rotation of the latter when the former is rotated.

When tightening the clamp screws 11, the division slits 21 will open, due to the tapered head 20, and force the divisions of the body outward at the points 24 and thereby clamp the cutters tightly against the walls of the slots.

In order to further facilitate this clamping of the cutters, the relief slits 25 may be cut into the front end of the body similar to the slits 21 but, preferably, from the bottom of the slots inwardly as shown in Fig. 2. This further division of the front end of the body provides more flexibility to the portions 27 and materially increases the efficiency of the clamping mechanism.

While the reamer is in use as well as while the cutters are being adjusted, the faces 15 of the cutters abut on the faces 17 of the ring 8; if these faces 15 and 17 are inclined too much to the horizontal axis of the reamer, the longitudinal movement of the ring 8 has a tendency to wedge the rear end of the cutters downward and lift the

front end thereof off of the bottoms of the slots. Therefore, the inclination of the faces 15 and 17 should be arranged so that the cutters are prevented from leaving the bottom of the slots while adjusting the cutters but have sufficient angularity to hold the same down upon the bottom of the slots. 55

When the reamer is adjusted and locked, the ring 8 forms a longitudinal abutment for the cutters and also holds them down 60 upon the bottom of the slots in addition to the function of moving the cutters longitudinally while adjusting the same.

The bottoms of the slots and of the cutters may be made parallel with the longitudinal axis of the reamer when it is desired 65 to construct a diametrically non-adjustable reamer but wherein the cutters can be adjusted longitudinally to the end that the front face of the cutters may be adjusted 70 to any desired distance outside of the front end of the body; to face the bottom of a hole for instance, or when grinding the front face of the cutters.

Without limiting myself to the precise 75 construction shown and described,

I claim:

1. A reamer comprising a body provided with slots and with a division slit between each alternate pair of these slots and with 80 a relief slit terminating in each of these slots, a cutter in each of said slots, and a cone headed screw through each of said division slits and threaded into said body and adapted to force the front and divided 85 portions of said body against said cutters.

2. A reamer comprising a body provided with slots extending the entire length of the main body portion and with a division slit between each alternate pair of these 90 slots and extending part way into the front end of this body and with a relief slit terminating in each of these slots and extending part way into the front end of this body, and a cone headed screw through each 95 of said division slits and threaded into said body and adapted to force the front and divided portions of said body against said cutters.

WM. E. KELLY.
